METALLURGICAL APPARATUS

Jesse O. Betterton, Metuchen, and Karl A. Lindner, Rahway, N. J., assignors to American Smelting and Refining Company, New York, N. Y., a corporation of New Jersey

Application December 27, 1934, Serial No. 759,358

6 Claims. (Cl. 266—33)

In the treatment of secondary metals for the recovery of the components thereof in a refined condition suitable for marketing, the success of the operations is dependent upon the efficiency 5 in which the metals and by-products of the treatment thereof are recovered.

A large supply of such secondary metals lies in the great quantity of scrap radiators for internal combustion engines which is available. Such 10 radiators, as well as many other varieties of scrap, have associated with them rather substantial quantities of solder, which constitutes a valuable by-product in the treatment of such scrap.

15 In view of the relatively low melting point of this solder, the practice generally is to subject the solder-bearing scrap to a preliminary low temperature sweating operation which is intended to melt off the solder which is collected and 20 marketed as such after only relatively minor treatment. The melting of this solder causes disintegration of the scrap, however, with the result that much of the solder remains adhering to the disintegrated scrap and does not flow away there- 25 from to the collecting pans.

One object of the present invention is to provide an improved type of furnace in which the solder of solder-bearing scrap may be melted and freed from the scrap in a substantially more 30 expeditious manner than has heretofore been possible.

A further object of the invention is to provide 35 a furnace of the above indicated character which includes mechanism whereby the scrap radiators or other articles may be subjected to agitation or shaking action during the sweating operation, whereby the solder is effectively liberated from the scrap as it is melted.

A still further object of the invention is to provide 40 a furnace of the indicated character in which there are provided readily controllable heating means disposed so as to uniformly heat the furnace to the desired temperature, while preventing overheating thereof and while maintaining 45 substantially constant atmospheric conditions in the furnace during the sweating operations.

Further objects and advantages of the present 50 construction will become apparent as the description proceeds, and the features of novelty will be pointed out particularly in the appended claims.

The present invention embraces the thought that if the radiators or other solder-containing 55 scrap be shaken or otherwise agitated during the

sweating operation, the molten solder will be more freely released therefrom, so that the direct yield of readily marketable solder will be substantially increased.

In the accompanying drawing—

Fig. 1 is a sectional elevation through one form of the improved furnace, the heating chamber of the furnace being shown in section to illustrate the mounting of the shaking table and disposition of the heating elements, the mechanism for imparting movement to the shaking table being shown in elevation, parts thereof being broken away for clarity, the view also showing, in dotted lines, the position of the shaking table when in discharging position.

Fig. 2 is a plan view of the shaking table of Fig. 1.

Fig. 3 is sectional view on the line 3—3 of Fig. 1, looking in the direction of the arrows, the scrap-receiving basket, however, being omitted.

Referring more particularly to the drawing, it will be seen that the apparatus of the present invention comprises the furnace A in which is mounted a melting compartment B and a plurality of the heating elements C.

The furnace A is built up of refractory walls 5, the melting compartment B being supported thereon so that the bottom 7 of the compartment is inclined at a sufficient angle to enable melted solder metal to run freely through the solder outlet 9 into suitable receiving molds, not shown. The compartment B is formed of sheet steel and is mounted on angles 11 suitably anchored to the furnace walls and extending along the side and end walls of the furnace A. The chamber B is 35 provided with a removable cover 13, also of sheet steel, provided on its underside with a layer of heat insulating material 15. The cover 13 is provided adjacent to its upper end with an opening 17 adapted to receive the basket-supporting member 19.

As will be apparent from the drawing, there is positioned in the compartment B a basket 21, which is adapted to receive the radiators or other scrap to be treated.

This basket 21 comprises a frame made up of a bottom 23, sides 25 and 27 and ends 29 and 31. The basket 21 is pivotally mounted at 33 on rod 35 mounted in the side walls 12 and 14 of the heating chamber B. The bottom of basket 21 is 50 formed by the transversely extending spaced bars 37 which carry the radiators or other scrap and which also reinforce the sides 25 and 27 of the basket. The bars 37 are suitably welded or otherwise secured, to the sides 25 and 27 and also 55

to the longitudinally extending bar 39. The spaces 41 between the bars 37 form egress openings for the molten solder which runs therethrough to the inclined bottom 7 of the compartment B, and is guided through the outlet 9 by the end walls 43 and 45 which converge to the outlet 9.

The scrap-receiving basket 21 is supported at one end by the pivot bar 35 and at the other end by a suitable releasable support of any kind, illustrated as a hook member 19 which is passed through a suitable opening in the end 31 of the basket 21. This hook member 19 connects the basket 21 with a shaking beam 47, operation of which agitates the basket 21 and the scrap 15 thereon.

As will be seen from the drawing, the beam 47 is pivotally connected at the horizontal pivot 49 to the upright supporting beam 51 suitably anchored to the floor 53. The pivot 49 is adjacent 20 to one end of the beam 47, the hook 19 being connected to the beam adjacent to the other end. The beam 47 is thus free to be vertically reciprocated about pivot 49, as shown by dotted lines in Fig. 1.

The mechanism for shaking the beam 47 is contained in the housing 55. This mechanism comprises a cam 57 mounted on a shaft 59 which is operated, through any suitable standard type speed reducing mechanism, not shown, by a motor 61; or the speed of the motor may be controlled by a rheostat or other means. The shaft 59 is supported in bearings 63 and 65 suitably secured to the housing 55. Also illustrated as being mounted on the housing 55 and anchored thereto is an upright 67 provided at its upper end with a stop 69 which engages the shaking beam 47 and acts as a stop for the beam 47 on the downward stroke of the beam. The standard 67 is provided with an outstanding arm or bracket 71 terminating in a vertical bearing 73 through which passes a rod 75, this rod being connected at 77 with the shaking beam 47 and, extending into the housing 55, rides on the surface of the cam 57, the end 79 of the rod being in continuous engagement with the cam 57 so that as the cam 57 rotates, the rod 75 will be moved up and down to vibrate or to shake the bar 47, thereby vigorously shaking or jarring the basket 21. A bearing 81 may be provided for the rod 75 at the housing 55.

The furnace A and compartment B are heated by heating units C comprising a suitable number of electric heaters 83, the drawing showing four such heaters disposed longitudinally of the furnace, with a fifth heater extending transversely of the furnace. The use of electric heating apparatus enables a close control of the temperature and any complications of operating conditions resulting from the presence of combustion gases are avoided, there being maintained a more uniform composition of the furnace atmosphere than in the case where a gas- or oil-fired furnace is used.

In operation, the cover 13 is removed and the scrap radiators or other materials are placed in the basket 21, the furnace A together with compartment B having been brought up to a temperature sufficiently high to melt the solder in the scrap. The cover is replaced, and the motor 61 started, thus operating the cam 57, the basket 21 being vigorously vertically shaken by the motion transmitted from the cam through the rod 75 and the bar 47. The solder, as it melts, runs through the spaces 41 and down the inclined bottom 7 of

the compartment B, thence out through the outlet 9.

It will be observed that the bottom 23 of the basket 21 is inclined at substantially the same angle as the bottom 7 of the compartment B. This inclination, coupled with the shaking action of the basket 21, causes the scrap to move towards the lower end of the basket. This movement, together with the jarring of the materials in the basket, effectively frees the molten solder from the materials, and prevents the same from becoming entrapped in the materials, thereby very materially increasing the yields of solder in a condition ready for market, with at most only 15 relatively slight treatment being required for its fulfillment of market requirements.

The scrap, after the solder has drained off, is discharged from the basket 21 by stopping the motor 61, removing the cover 13, disengaging the hook 19 from the basket 21 and lifting the basket around pivot 35 into its dumping position as indicated by the dotted lines of Fig. 1, the sweated materials being thereby dumped from the basket.

In Fig. 1, numeral 85 represents a reinforcing brace for the basket 21.

It will be seen from the drawing that the compartment B, in practice, is a metallic receptacle which is inserted as a unit in the heating chamber of the furnace A, and which is installed 30 in the heating chamber in sloping position so that its outlet for the sweated solder or other metal is at the lowest level. The heating elements 83 are positioned beneath the sloping bottom 7 of the receptacle B so that certain of these 35 heating elements are positioned longitudinally of the receptacle B while other of these heating elements are positioned transversely of the receptacle B, and beneath the lowest portions of the receptacle, so that the sweated solder in 40 the receptacle B will be subjected to a continuously increasing amount of heat as it moves towards the outlet, so that the sweated metal will be freely molten and liquid for free passage through the outlet, it being sufficiently hot as it 45 passes through the outlet so that there will be no tendency for solidification of the sweated metal until it has passed clear from the furnace.

It will be apparent that the present invention is not restricted to the specific details of construction herein illustrated and described, it being obvious that these details may be varied relatively widely without departing from the spirit of the invention, as will become readily apparent to those skilled in the art; and it will be understood, therefore, that it is intended and desired to embrace within the scope of this invention such modifications and changes as may be necessary to adapt it to varying conditions and uses.

What is claimed is:—

1. A metallurgical furnace comprising the combination with a heating chamber, of a material-receiving receptacle therein, mechanism for shaking the receptacle, and a pivotal mounting enabling the receptacle to be turned outwardly from the furnace on the mounting and inverted into dumping position.

2. A metallurgical furnace comprising the combination with a heating chamber, of a material-receiving basket having a perforate bottom therein, mechanism for shaking the basket, and supporting means for the basket including a pivotal mounting therefor at one end of the basket adjacent the upper edge thereof.

and releasable securing means cooperating therewith, the securing means being positioned opposite to the pivotal mounting, the basket being thereby suspended on the mounting and securing means, whereby upon release of the securing means the receptacle may be swung vertically about its pivotal mounting into inverted dumping position.

3. A furnace for separating lower melting from higher melting metals and alloys, comprising the combination with a heating chamber, of heating elements within the chamber, a sweating compartment within the heating chamber, the said compartment having a bottom inclined to a discharge opening, a receptacle in the sweating compartment for receiving metal to be sweated, a pivotal mounting for the receptacle enabling the said receptacle to be turned upon the mounting and thereby swung upwardly and outwardly from the sweating compartment and into inverted dumping position, and mechanism for shaking the receptacle, the said mechanism comprising a bar pivotally supported for free vertical movement, suspending means for the receptacle connecting the bar and receptacle, the said means being releasable from the receptacle for enabling the receptacle to be swung from the melting compartment into dumping position, actuating means secured to the bar, and means for imparting vibratory movement to the said actuating means.

4. A furnace for separating lower melting from higher melting metals and alloys, comprising the combination with a heating chamber, of heating elements within the heating chamber, an inclined sweating compartment positioned within the heating chamber and having a bottom sloping towards a discharge opening for sweated metal, and a perforate receptacle suspended in the sweating compartment for receiving material to be sweated, the said sweating compartment and receptacle therein being positioned relatively to the heating elements in the heating chamber so as to subject the metal sweated from the said material in the receptacle to increasing heat as the said metal flows to the discharge opening, thereby maintaining the metal sufficiently fluid for it to drain thoroughly through the discharge opening.

5. A furnace for separating lower melting from higher melting metals and alloys, comprising the combination with a heating chamber, of heating elements within the heating chamber, a receptacle mounted in the heating chamber forming an inclined sweating compartment, a perforate holder suspended within the said receptacle for receiving material to be sweated, the said receptacle having a discharge opening at its bottom and at one end thereof, and being inclined so that metal sweated from material in the holder will drain through the said discharge opening, a pivotal mounting in the sweating compartment for the holder enabling the said holder to be swung upwardly and outwardly from the sweating compartment and into inverted dumping position, releasable means for suspending the holder in the sweating receptacle, and mechanism for vertically shaking the suspending means and holder, the said mechanism comprising a lever pivotally supported for free vertical movement, an actuating arm secured to the lever, an abutment engaged by the lever on its downward stroke, and mechanism for imparting vertical reciprocatory motion to the said actuating arm.

6. A furnace for separating lower melting from higher melting metals and alloys, comprising the combination with a heating chamber, of heating elements within the heating chamber, a container adapted to be inserted as a unit in the heating chamber to form a sweating compartment, the said container being provided with an outlet opening and being installed in the heating chamber in sloping position with the outlet opening at the lowest level so that sweated metal will flow through the outlet, a perforate holder in the said container for receiving materials to be sweated, certain of the said heating elements extending longitudinally of the said container, other of the heating elements extending transversely of the container beneath the lowest portion thereof for imparting maximum heat to the sweated metal for maintaining the said metal freely liquid for discharge through the discharge opening, and mechanism for vertically shaking the said holder.
